(57) **CLAIM**

The ornamental design for a dispensing device, as shown and described.

DESCRIPTION

FIG. 1: Top view of the dispensing device

FIG. 2: Bottom view of the dispensing device

FIG. 3: Front view of the dispensing device

FIG. 4: Right side view of the dispensing device

FIG. 5: Left side view of the dispensing device; and,

FIG. 6: Back side view of the dispensing device.

All surfaces not shown form no part of the claimed design. The broken lines shown in the drawing views of FIGS. 3, 4, 5 and 6 represent portions of the dispensing device that form no part of the claimed design.
